DESIGN FOR AN ADDING MACHINE

Willis A. Kropp, Chicago, Ill., assignor to Victor
Adding Machine Company, Chicago, Ill., a cor-
poration of Illinois

Application June 30, 1939, Serial No. 85,783

Term of patent 14 years

To all whom it may concern:

Be it known that I, Willis A. Kropp, a citizen
of the United States, residing at Chicago, in the
county of Cook and State of Illinois, have in-
vented a new, original, and ornamental Design
for Adding Machines, of which the following is
a specification, reference being had to the ac-
companying drawing, forming a part thereof.

Figure 1 is a side elevation of an adding ma-
chine, showing my new design.

Figure 2 is a plan view of the same machine.
Figure 3 is a front elevational view of the same
machine.

Figure 4 is a rear elevational view of the ma-
chine.

I claim:
The ornamental design for an adding machine,
as shown.

WILLIS A. KROPP.
